(57) **CLAIM**

The ornamental design for a vehicle front upper bumper cover, as shown and described.

DESCRIPTION

FIG. 1 is a front elevational view of a vehicle front upper bumper cover showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top, front and left side perspective view thereof;

FIG. 8 is a bottom, front and left side perspective view thereof; and,

FIG. 9 is a top, rear and left side perspective view thereof. The broken lines that represent an internal boundary and the area within the broken lines do not form no part of the claimed design.
